UNITED STATES PATENT OFFICE.

ZEBULON L. CHADBOURNE, OF NEW BRIGHTON, NEW YORK.

TAKE-UP MECHANISM FOR LOOMS.

SPECIFICATION forming part of Letters Patent No. 695,373, dated March 11, 1902.

Application filed September 21, 1901. Serial No. 76,057. (No model.)

To all whom it may concern:

Be it known that I, ZEBULON L. CHADBOURNE, a citizen of the United States, residing at New Brighton, in the county of Rich-
mond and State of New York, have invented
5 new and useful Improvements in Take-Up
Mechanisms for Looms, of which the follow-
ing is a specification.

My invention relates to a take-up mechanism
10 for looms. This mechanism is particu-
larly designed to be used on a hammock-loom
covered by application for patent, Serial No.
59,118.

The object of my invention is to construct
15 an intermittent take-up which, in combina-
tion with a drum driven by a friction-motor,
will keep the fabric taut. The novel construc-
tion by which this object is attained is fully
described in this specification and illustrated
20 in the accompanying drawings, forming a part
thereof, in which—

Figure 1 is a plan view of the rear portion
of my loom with my device attached thereto.
Fig. 2 is a side elevation of the same. Fig. 3
25 is a vertical longitudinal section of the same.
Fig. 4 is a detail of the gearing. Fig. 5 is a detail
of the four-armed cam. Fig. 6 is a detail
of one of the pins and spring, together
with fragments of the disks.

30 Like numerals of reference designate like
parts in the different views of the drawings.

The numeral 1 designates the rear frames
of the machine, and 2 a pin-bearing sag-roller
35 on which the fabric rests after passing from
the weaving mechanism of the machine. Located
just back of the sag-roller 2 are two feed-
rollers 3 and 4—a lower large one and an upper
smaller one, respectively. The lower roller
40 3 is supported on spindles 5 and 6 and the upper
roller 4 is supported on spindles 7 and 8. The
spindle 5 has keyed thereon a gear 9, which
meshes with a smaller gear 10, keyed on the
spindle 7. The ratio of the diameters of the
gears 9 and 10 is equal to the ratio of the
45 diameters of the rollers 3 and 4. The spindles
7 and 8 are mounted in boxes 11 and can be
vertically adjusted by means of set-screws 12,
carrying sliding blocks 13, within which the
spindles fit.

50 In order to drive the feed-rolls 3 and 4, a
gear 14 is keyed on the spindle 6, which gear
meshes with a gear 15, mounted to turn on a

stub-shaft 16 and having a hub bearing a
ratchet 17. A pair of pawls 18 mesh with
the ratchet 17 and are carried by a lever 19, 55
fulcrumed on the shaft 16. The outer end of
the lever 19 is slotted at 19^a, and the upper
end of a connecting-rod 20 is pivoted thereto
on a bolt 20^a, adjustably mounted in said slot.
By this arrangement the throw of the lever 60
19 can be regulated. A ratchet 21 is keyed
on the outer end of the spindle 5 and is en-
gaged by a pawl 21^a, mounted on the frame.
This combination of pawl and ratchet pre-
vents slackening off of the feed when the pawls 65
18 are taking a new hold.

The lower end of the connecting-rod 20 is
pivoted to the long arm 22^a of a bell-crank
lever 22, whose short arm 22^b bears a roller
23, which is positioned to be engaged by the 70
arms 24^a of a four-armed cam 24, keyed on
a main shaft 25. The shaft 25 has a beveled
gear 26 keyed thereon, which beveled gear
meshes with a second beveled gear 27, keyed
on a shaft 28, which is driven by some source 75
of power.

The gearing is so proportioned that at each
movement of the weaving mechanism one of
the arms 24^a will engage the roller 23 and ac-
tuate the connecting-rod 20 to operate the le- 80
ver 19 to turn the rollers 3 and 4 to feed the
fabric which passes between them.

The fabric passes from the rollers 3 4 to a
drum 29, which is located in the extreme rear
of the machine and is supported on spindles 85
30, journaled in open boxes in the frame of
the machine. For driving the drum 29 a
friction-motor is provided. This motor com-
prises a disk 31, slidingly mounted on the
right spindle 30, adjacent and parallel to a 90
disk 32, keyed on said spindle. The disk 32 has
a threaded aperture 33 in each quadrant,
within which are mounted pins 34, surrounded
by coiled springs 35 and having enlarged
grooved heads 36, provided with threads and
screwed into the apertures 33. The pins 34
fit loosely apertures 37 in the disk 31, and
the springs 35 bear at their outer ends on
this disk. This pressure can be regulated by
turning the heads 36. By the pressure of the
springs 35 the inner face of the disk 31 is held
in contact with a large friction-disk 38,
mounted on a stub-shaft and driven by a pul-
ley 39, connected thereto by a hub 39^a. The

pulley 39 is driven by means of a belt connecting it to a pulley 41, keyed on the main shaft 25. By this arrangement of a drum driven by a friction-motor the pull on the fabric is maintained constant and does not vary with the amount of fabric on the drum.

It should be noted that the right spindle 30 is made in sections secured together by a cross-pin 42. This enables the drum to be 10 replaced when full by an empty one.

Having described my invention, what I claim as new, and wish to secure by Letters Patent, is—

1. In a take-up mechanism, the combination with a drum designed to wind fabric on as the weaving progresses, of a friction-disk loosely mounted on one spindle of said drum and having apertures therein, of a disk rigidly mounted parallel to said friction-disk and 15 having threaded apertures therein, pins fitting apertures in said friction-disk and having enlarged threaded heads fitting said threaded apertures in said rigidly-mounted disk, springs mounted on said pins and a friction-disk mounted to bear on said first-mentioned friction-disk, substantially as described.

2. In a take-up mechanism, the combina-

tion with a drum constructed to wind fabric on and bearing a spindle, of a friction-disk 30 slidingly mounted on said spindle, of a disk mounted on said spindle parallel to said friction-disk, springs mounted on said disk and bearing on said unyielding friction-disk, and a second friction-disk mounted to contact 35 with and actuate said friction-disk on said spindle, substantially as described.

3. In a take-up mechanism, the combination with a drum provided with a spindle, of a friction-disk loosely mounted on said spindle and having apertures therein, of a disk 40 rigidly mounted on said spindle parallel to said friction-disk, pins adjustably mounted in apertures in said fixed disk and engaging said apertures in said friction-disk, springs surrounding said pins and bearing on said friction-disk, and a second friction-disk mounted 45 in contact with said first-named friction-disk, substantially as described.

In testimony whereof I have hereunto set 50 my hand in presence of two subscribing witnesses.

ZEBULON L. CHADBOURNE.

Witnesses:

FRANK G. RADEFINGER,
BENNETT S. JONES.
